UNITED STATES PATENT OFFICE.

SAMUEL CHARLES TURNER, OF EAST PROVIDENCE, RHODE ISLAND.

MACHINE FOR AUTOMATICALLY FOLDING GOODS IN VATS.

SPECIFICATION forming part of Letters Patent No. 717,950, dated January 6, 1903.

Application filed May 8, 1902. Serial No. 106,453. (No model.)

To all whom it may concern:

Be it known that I, SAMUEL CHARLES TURNER, a resident of East Providence, in the county of Providence and State of Rhode Island, have invented certain new and useful Improvements in Machines for Automatically Folding Goods in Vats; and I do hereby declare that the following is a full, clear, and exact description thereof, reference being had 10 to the accompanying drawings, and to the letters of reference marked thereon, which form a part of this specification.

This invention relates to automatic plaiting-machines for goods in process of bleaching, and has for its object to fold the fabric, which is delivered to it in a rope form, in layers in a bin or keir to facilitate the process of bleaching of the goods.

It is fully explained and illustrated in this 20 specification and the annexed drawings.

Figure 1 represents a plan view of the machine. Fig. 2 is a sectional side elevation on line 2 2, Fig. 1, showing the machine in position on a keir and representing the fabric as delivered in a rope form and being folded or plaited in the keir. Fig. 3 represents a front elevation of the machine. Fig. 4 shows a perspective view of the plaiting-trough and the operating-cams. Fig. 5 is a perspective view 30 of the traversing guide-eye by which the goods are led back and forth across the machine. Fig. 6 is an enlarged sectional elevation of the hub of the guide-eye which surrounds the traversing-screw, showing the dog which engages the thread. Fig. 7 is a perspective view 35 of the dog.

In the construction of the machine, A is the main frame, on which is mounted the longitudinally-movable carriage, of which B B are 40 the side frames, and in these side frames are the bearings for the traverse feed-screw C and the delivery reel or cylinder D.

E is the reciprocating plaiting-trough hung on arms e e, (see Fig. 4,) which are pivoted 45 on the reel-shaft d and extend out under the revolving cams c c, fixed to the screw-shaft C and from which motion is received. The guide-eye F is also mounted on the revolving screw-shaft C and receives its traverse motion 50 back and forth across the frame by means of the dog f, which is loosely mounted in its hub (see Fig. 6) and which engages the thread of

the screw. This dog f is inserted into the hub through the slotted boss a, made to receive it, and is held in place by the screw b. 55 The guide-eye is kept in an upright position by the guide-shaft g, which passes through the slot of the downwardly-extending arm h.

G is the driving-shaft, on one end of which is mounted the tight and loose driving-pulleys H H. The bevel-gear J is held to turn with and slide along the driving-shaft G and is supported by the bracket i, which is attached to the movable frame B. This gear is for the purpose of transmitting motion from 65 the main shaft through the gear K to the delivery-reel, on the shaft of which gear K is fixed. The reel in turn transmits motion to the screw-shaft C through the sprocket-chain and gears n n. A slow and intermittent motion 70 is transmitted from the driving-shaft to the cross-shaft M through the worm j, gear k, and intermittent gears l and m and gear p. On each end of the shaft M are the sprocket-wheels N and O, which are connected through 75 the sprocket-chains P P and sprocket-wheels W W on the opposite end of the machine to both ends of the movable frames B B and transmit to them an intermittent longitudinal motion along the main frame A. The bevel-gears R R mesh into the intermediate gear S and are mounted loosely on the shaft M.

t is a clutch which is keyed to slide on the shaft and engage with either of the gears R R.

A reverse motion of the carrying-frames is 85 obtained by the reversing-lug w bringing up against the stop-collars r r, fixed on the shipping-rod s, which throws the clutch t, by the knee-lever V, from one gear into the other.

The operation of the machine is as follows: 90 The fabric T is first threaded through the guide-eye F and passed over the delivery-reel D, down through the plaiting-trough E. When the machine is started, the weight of the goods bearing on the revolving reel feeds 95 itself continuously into the keir or bin, where it is plaited or laid in folds by the reciprocating plaiting-trough E and at the same time is carried by the traversing guide-eye F across the machine. After one layer has been laid 100 across the machine the intermittent motion moves the carriage longitudinally along the width of the fold and another layer is plaited in the keir as the traversing guide returns,

and so it is continued, folding back and forth as it feeds across the keir and moving along longitudinally each time a row is laid until the end of the keir is reached, when this feed 5 is automatically reversed and the carriage returns as it came, these motions continuing until the keir is filled. The frame of the machine is mounted on rollers Z and is suspended on a track L above a row of keirs or bins c T', so that when it has filled one keir by its automatic mechanism just described the machine is moved along over the next keir, where the same process is repeated, and so on until all of the keirs in the row are full.

15 Having thus described my improvement, what I claim as my invention, and desire to secure by Letters Patent, is—

1. In a machine of the character described the combination of a main frame, a longitudinally-movable carriage and means for moving same, a delivery-reel for drawing in the goods, means for carrying the goods transversely back and forth across as they are fed in the machine, means for giving the goods a 25 folding motion, substantially as described.

2. In a machine of the character described, a main frame, a carriage arranged to move longitudinally along said frame, means for moving said carriage, means for delivering 30 textile fabric in a rope form to the keir, means for giving said fabric a folding motion in combination with means for simultaneously feeding it transversely across the machine, substantially as described.

35 3. In a machine for feeding textile fabrics into a keir in a rope form, a frame, a longitudinally-movable carriage mounted on said frame, said carriage carrying on it a delivery-reel, a transversely-movable guide and an oscillating guide-trough for folding the goods, in combination with means for driving the 40 same, substantially as described.

4. In a machine for feeding textile fabrics into a keir in a rope form, a frame, a longitudinally-movable carriage mounted on said 45

frame, said carriage carrying on it a delivery-reel, a screw-shaft, a transversely-movable guide-eye mounted on said screw-shaft, and an oscillating guide-trough for folding the goods, in combination with means for feeding 50 the goods continuously to the keir, and means for feeding the carriage longitudinally, and intermittently back and forth automatically along said frame, substantially as described.

5. In a machine for feeding textile fabric 55 into a keir in a rope form, a frame, a longitudinally-movable carriage mounted on said frame, said carriage carrying on it a delivery-reel, a screw-shaft, a transversely-movable guide-eye mounted on said screw-shaft, and 60 an oscillating guide-trough for folding the goods, in combination with a main driving-shaft, gears for transmitting motion from said driving-shaft to an end shaft, sprocket-wheels mounted on said end shaft which impart motion 65 to said carriage through a chain, a bevel-gear mounted on said driving-shaft for imparting motion to mechanism mounted on said carriage, substantially as described.

6. In a machine for feeding textile fabrics 70 into a keir in a rope form, a frame, a longitudinally-movable carriage mounted on said frame, said carriage carrying on it a delivery-reel, a screw-shaft, a transversely-movable guide-eye mounted on said screw-shaft, and an 75 oscillating guide-trough for folding the goods, in combination with means for feeding the goods continuously to the keir, and means for feeding the carriage along longitudinally a predetermined distance when the traverse 80 feed has reached the side of the frame, means for reversing the traverse feed, and means for reversing the longitudinal feed, substantially as described.

In testimony whereof I have hereunto set 85 my hand this 28th day of April, A. D. 1902.

S. CHARLES TURNER.

In presence of—

HOWARD E. BARLOW,
M. L. HAZARD.
